UNITED STATES PATENT OFFICE.

ALBERT H. WHITEHEAD, OF HOOD RIVER, OREGON.

COLLAR-FASTENER.

1,280,605.

Specification of Letters Patent.

Patented Oct. 1, 1918.

Application filed March 31, 1917. Serial No. 158,918.

To all whom it may concern:

Be it known that I, ALBERT H. WHITEHEAD, a citizen of the United States, residing at Hood River, in the county of Hood River and State of Oregon, have invented certain new and useful Improvements in Collar-Fasteners, of which the following is a specification.

This invention relates to an improvement 10 in collar fasteners, and more particularly to a device of this character intended for use in securing a laundried or soft collar in place upon the band of a shirt or waist, at the back of the neck.

15 An object of my invention is to provide a fastener adapted to take the place of the usual button as employed in the connection mentioned and which device may be cheaply and simply manufactured by bending up to 20 the proper shape a single blank of sheet metal or other suitable material.

A further object resides in so constructing the fastener that a tongue is extended in hooked formation from a body portion, 25 which body portion has a pair of side extensions substantially at the base of the tongue as bent over to form the hook, thereby producing channels or recesses at the sides of the tongue to receive that part of the neck 30 band adjacent the button hole, and thus secure the device in the button hole, while at the same time the turned back portion of the tongue will prevent downward movement of the collar due to the fact that the 35 band of the collar will be naturally drawn in whereas the neck band is forced outwardly.

Yet another object lies in providing a collar fastener which presents that part extending through to secure and hold the collar in place to be of such form that when used in connection with turn over collars the tie will lie smoothly and slide freely thereover in the adjustment of the tie where- 45 as when employed in connection with standing collars the tie can be fitted beneath the bent down tongue portion and will then be held against riding up on the collar.

With the above and other objects in view, 50 which will be in part described and in part understood from the specification, drawing, and claim, my invention consists in certain novel features of construction and combinations of parts which will be hereinafter more fully set forth.

In the drawings:—

Figure 1 is a fragmentary sectional view taken through a collar and the neck band of a shirt and showing my improved fastener applied therewith;

Fig. 2 is an elevational view of the fastener; and,

Fig. 3 is a view showing the blank as the same will appear before the tongue is bent or folded back.

The blank from which the fastener is bent up, the form of which is better shown in Fig. 3, includes a body portion 1 which has a tongue 2 extending therefrom and side extensions 3 and 4 formed on each side of the tongue. The side extensions are so shaped that recesses 5 and 6 are provided between the same and the tongue 2, and as the tongue is bent or folded back after the manner shown in Figs. 1 and 2, these recesses are 70 presented on each side of the turned back portion of the tongue to thus give the extensions 3 and 4 substantially the form of hooks. To facilitate insertion of the tongue through a button hole, it is perhaps preferable that the ends be bent outwardly from a parallel relation with respect to the body portion, as is better shown in Fig. 1.

In use, the fastener will preferably be fitted in the button hole of the neck band of the shirt before the same is put on, and to accomplish this operation the tongue 2 is fitted through the button hole to bring the body portion 1 against the inner side of the band with the bent over portion of the 90 tongue received through the button hole. In making up neck bands for shirts or waists, it is customary to provide a pocket at the back of the band and to form the button hole through the outer layer of fabric making up 95 the pocket, and thus it will be seen that when the fastener is fitted in the relation set forth, the body portion 1 will not have bearing against the neck of the wearer, however, if desired, the fasteners might be made up of 100 celluloid or other suitable material of a like nature and then could be used upon shirts or waists having the button hole formed entirely through the neck band, and it of course being understood that a fastener 105 made up of sheet metal could be used in the same way provided the metal be of such character that it will not discolor or poison the skin. The fitting of the fastener through the button hole presents the parts 110

in such form that as the fastener is pulled or drawn upwardly, the upper edge of the button hole will be caught in the recesses 5 and 6, and the fastener will be held against 5 pulling through the button hole by the extensions 3 and 4, whereas the fastener is held against displacement from downward strain through the fact that the tongue is fitted through the button hole. The slight 10 outward bending of the tongue 2 presents the same in such form that a collar may be very readily hooked thereover and then if the collar is moved upwardly with the tongue fitted through the button hole, it 15 will be brought to a position that the band fits closely against the neck band of the shirt and the collar will be held against upward shifting by reason of the fact that the tongue is hooked therethrough whereas 20 downward slipping movement will be precluded by the extension of the bent portion of the tongue through the button hole of the collar band, and by reason of the fact that the collar is drawn in rather tightly 25 against the neck band when the collar is fitted in place.

From the foregoing it will be seen that I have provided a collar fastener which may be more cheaply manufactured than the 30 usual forms of collar button, which does not pull in through the pressure of the collar and punch into the neck of the wearer, and which lies flat within the fold of a turn over collar to thus preclude interference with adjustment of the tie, while at the same time affording a hook under which the tie may be caught when the fastener is used with a standing collar to hold the tie from riding up on the collar; the parts being shaped and 35 formed to hold securely within the button holes of the neck band and the collar and to thus positively preclude the possibility of the collars shifting or accidentally loosening.

Copies of this patent may be obtained for five cents each, by addressing the "Commissioner of Patents, Washington, D. C."

While in the foregoing I have set forth 45 only one specific form and construction of the device and have specified only certain materials, it will be understood that the form might be varied, that other structures than those herein mentioned might be employed in the making of the fastener, and that a number of changes and variations might be resorted to in the device without departing from the spirit and scope of my invention, in view of which fact I wish to 50 be limited only to such points as may be set forth in the claim.

I claim:

A collar fastener comprising an arcuate flat body forming points at the upwardly 60 directed corners of said body, a tongue extended from the center of the straight edge of said body and between said points, the tongue being bent back upon itself substantially parallel with the body and adapted 65 for engagement through the registering openings of the back of the shirt band and a collar, the bent back or bight portion of the tongue preventing downward movement of the fastener within said shirt band, the 70 points of said body extending upwardly upon either side of the portion of the tongue connecting with the body, the pockets formed between the points and the opposite portion of the tongue having seated therein 75 the opposite end walls of the button hole in the shirt band upon an upward movement of the fastener within said button hole, said point preventing the fastener from being drawn out of the button hole of the shirt 80 band.

In testimony whereof I affix my signature in presence of two witnesses.

ALBERT H. WHITEHEAD.
